Primary Examiner — Janice Hallmark(74) *Attorney, Agent, or Firm* — McGarry Bair PC(57) **CLAIM**

The ornamental design for a ceiling fan light kit, as shown and described.

DESCRIPTION

FIG. 1 is a bottom perspective view of a ceiling fan light kit, shown in the environment of a ceiling fan, showing my new design;

FIG. 2 is a top perspective view of the ceiling fan light kit of FIG. 1, having the ceiling fan environment removed;

FIG. 3 is a top view thereof;

FIG. 4 is a bottom view thereof;

FIG. 5 is a front side view thereof;

FIG. 6 is a rear side view thereof;

FIG. 7 is a right side view thereof; and,

FIG. 8 is a left side view thereof.

Portions of the ceiling fan light kit and ceiling fan environment are shown in broken lines and form no part of the claimed design.

1 Claim, 8 Drawing Sheets(56)
